UNITED STATES PATENT OFFICE.

ROBERT FARNHAM, OF PHILADELPHIA, PENNSYLVANIA.

CROSSTIE.

1,426,828.

Specification of Letters Patent. Patented Aug. 22, 1922.

Application filed June 22, 1921. Serial No. 479,449.

To all whom it may concern:

Be it known that I, ROBERT FARNHAM, citizen of the United States, residing at Philadelphia, in the county of Philadelphia and State of Pennsylvania, have invented 5 certain new and useful Improvements in Crossties; and I do hereby declare the following to be a full, clear, and exact description of the invention, such as will enable 10 others skilled in the art to which it appertains to make and use the same.

My invention consists of certain novel and useful improvements in rail road cross ties and has for one of its objects to provide a 15 cross tie of reinforced concrete, which when used in road building, will in effect present a continuous concrete road bed, a result which is very desirable where units of small weight are used to make up the whole.

Another object of my invention is to so 20 place the units, that when the weight of the moving load is made to rest on each unit, the said load is practically centrally placed over the supporting surface of the ballast, 25 thus securing a practically uniform bearing and preventing an unequal distribution of the load, the consequent rocking of the tie and its loosening in the ballast.

Another object which I have in view, is 30 the securing of the rail, to each individual tie, or to as many as may be deemed necessary, and thus prevent the creeping or longitudinal movement of the rail under traffic, and this object is aided by making the ends 35 of adjacent ties abut.

Another object which should be noted, is 40 that by my construction, the rail and entire track fastening including wooden blocks and steel channels, may be removed and re- placed without moving the tie proper from its position in the ballast, also any individual tie may be removed, without disturbing any 45 of the adjacent ties.

This is made possible by having none of 45 the track fastenings permanently secured to the tie.

As an additional object, my improved construction will prevent the accumulation of water in the openings or spaces between adjacent ties, thereby providing drainage for the ballast and road bed, a feature much to be desired in practice.

A further object which I have in mind, is 55 to provide the ties with means for withstand- ing the outward thrust of the moving load,

in addition to the resistance afforded by the block securing bolts.

A still further object of my invention, is to provide a single member to act as anchor- age for the bolts, securing the wooden blocks 60 to the tie, this single member acting both as an anchor plate and as a nut.

With the above and other objects in view which will appear as the description pro- 65 ceeds, the invention consists in the novel fea- tures herein set forth, illustrated in the ac- companying drawings and more particularly pointed out in the appended claims.

Referring to the drawings:

Fig. 1 is a plan view of two of my im- 70 proved cross ties, showing one rail in place.

Fig. 2 is a side view thereof.

Fig. 3 is a cross sectional view of Fig. 2, 75 showing the means for securing the rail to the tie.

Fig. 4 is a view taken on line 4—4 of Fig. 2.

Fig. 5 is a view taken on line 5—5 of Fig. 2.

Fig. 6 is a detail view of the steel rein- 80 forcement.

Fig. 7 is a view of the bottom of the block upon which the rail rests and which is se- cured to the cross tie.

Fig. 8 is a view of the metal channel which 85 is secured on the top portion of the wooden block.

1 designates the main body of my im- 90 proved reinforced concrete cross tie which is provided at each end with a T-shaped portion 2 having the edges thereof beveled as at 2'. Through the center of the cross tie and extending longitudinally thereof is a tubular recess 9 to receive a lock plate 10 adapted to be removably secured within said 95 recess. The lock plate is rounded on its upper surface, as shown in Fig. 4, to fit in the top of the recess 9, and is tapped at 10' to receive the bolts 7.

The bolts 7 pass through apertures 17 in 100 the wooden block 4, and secure the same to the tie. The top portion of the said block is cut away to receive the steel channel 4', which is also provided with apertures 17' adapted to register with the apertures in the 105 wooden block 4. The block 4 is provided on its under side and on opposite edges with re- cesses 13 to receive the nuts 14 of the bolts 6, which through the medium of eccentric washers 5, secure the rail 8 to the block. The 110

channel iron is provided with holes 13' to receive the bolts 6.

The body portion of the concrete cross tie is reinforced by means of longitudinally extending steel rods 11, and transverse rods 11^a which are wound around said longitudinal rods, as shown in Fig. 6. The T-shaped portions 2 of the cross tie are reinforced by the rods 11^b, which extend through the base thereof.

As shown in Fig. 5, the body of the tie 1 is preferably moulded larger at its base than at the top, in order to provide a greater supporting surface.

15 It will be noted that nothing but the steel reinforcements are permanently cast in the concrete, and any portion of the track or ties may be removed or replaced without the use of special tools.

20 The practical application of my improved concrete cross tie is obvious. The ties are laid in such a manner that the T-shaped portions 2 abut one another, as shown at 12 in Figs. 1 and 4. This prevents the creeping of the ties in the direction of the travel of the train, which is the case with ordinary ties.

25 After the ties are laid, they are packed around and tamped with ballast, thus forming when complete, practically an entire concrete road bed.

In order to prevent the settling of water in the spaces between the pairs of ties, I have provided recesses 12' (Fig. 4) in the base portion of the T-shaped cross sections.

30 When the road bed is complete the wooden blocks 4 together with the steel channels 4' are secured in place by means of the bolts 7 and the lock plates 10. The rails are then laid and by means of the bolts 6, the nuts 14 and the eccentric washers 5, which engage the flange of the rail, are secured in place.

35 To prevent the outward thrust of the rails and blocks, I provide a lug 15, which is cast in the concrete and serves to hold the blocks in place.

40 By means of the eccentric washers and the beveled flanges of the rails, it is possible to align the rails with little trouble. To accomplish this, the bolts 6 are loosened and

the rail moved in the direction desired. The 50 washers are then put in place and the bolts tightened again. The eccentric washers working against the beveled portions of the flange of the rail, will tend to hold the rail rigid.

55 To replace any part, or to lay a new rail, the above operation is simply reversed, the parts removed and new parts substituted therefor.

An important feature of my invention 60 consists in providing orifices in the tie for receiving the bolts or other track fastening means, as shown in the drawings, at such predetermined points that the said bolts or fastening means will at no time come into 65 contact with the steel reinforcements, thus obviating the necessity of insulating the rails to prevent short circuiting of electric current used for signalling.

The invention is not to be understood as 70 restricted to the exact details set forth, since they may be modified within the scope of the appended claims, without departing from the spirit and scope of my invention.

75 What I claim and desire to secure by Letters Patent is:—

1. A reinforced concrete cross tie which is provided with blocks for supporting rails, said blocks being recessed on their upper surfaces to receive a steel channel and on 80 their lower surfaces to receive a plurality of nuts, means for locking the said blocks to the body of the cross tie and means for securing rails to the said blocks.

2. A reinforced concrete cross tie which 85 provided with blocks for supporting rails, said blocks being recessed on their upper surfaces to receive a steel channel, and on their lower surfaces to receive a plurality of nuts, bolts and lock plates for locking said 90 blocks to the body of the cross tie and means for securing rails to said blocks.

3. A reinforced concrete cross tie as claimed in claim 2 wherein the means for securing the rails to the blocks consist in 95 eccentric washers.

In testimony whereof I affix my signature.

ROBERT FARNHAM.
